UNITED STATES PATENT OFFICE

2,031,633

GOLF BALL SCRUBBER

George A. Brillhart, Indianapolis, Ind.

Application July 26, 1935, Serial No. 33,312

2 Claims. (Cl. 15—97)

Golf ball washers as heretofore constructed provide brushes in pairs with the brush tufts turned toward each other and between which a golf ball is reciprocated in contact with the brush tufts. Such construction is objectionable because of the wear on the brush tufts which shortens them thereby requiring frequent readjustments and replacements of the tufts, and also because of the arduous hand labor of reciprocating the golf balls against the brushes.

The object of this invention is to scrub the surface of golf balls with sponges, making contact by crank instead of reciprocating movement, in a manner to rotate the ball and scrub all portions of its surface.

The object is to provide a device of the above character which is simple in construction, easy and efficient in operation, and which is readily accessible for placing and removing golf balls and for cleaning and renewing operative parts of the device.

I accomplish the above objects and other objects which will hereinafter appear by the mechanism illustrated in the accompanying drawing intended to assist the description but not to define the limits of the invention.

In said drawing—

Fig. 1 is a view in side elevation and partial vertical section of my invention in assembled form.

Fig. 2 is a top plan view.

Fig. 3 is a horizontal section on the line 3—3 of Fig. 1, looking down, and

Fig. 4 is a detail in vertical section on the line 4—4 of Fig. 1 looking inwardly.

Like characters of reference indicate like parts in the several views of the drawing.

Referring now more particularly to the drawing, the numeral 5 designates a container or receptacle cylindrical in shape and initially open at the top, which is provided with a removable cover 6, having a flange 7, which makes a close sliding fit around the outer top end of the container 5. The cover 6 is here shown as a truncated cone supporting a cylindrical dome 8. The top of the dome has a hole with a bearing 9 for one end of a shaft 10.

An outer continuation of the shaft is bent to form a crank 11 which terminates with an upward end bearing a hand knob 12 by which the shaft is manually rotated.

At a suitable distance above the bottom of the container 5 is a stationary web 13, having its ends cemented or otherwise fastened to the inner walls 55 of the container. The center of the web has a

hole with a bearing 14 in which the lower end of shaft 10 is removably journaled, to properly center the shaft in use, and to allow it to be withdrawn with the cover 6 when the latter is taken off.

A short distance above the web 13 is a metal plate 15 which is supported from the web by spring clips 16', which, as best illustrated in Fig. 4, comprise metal flanges 17' broadened outwardly into a head slidingly engaged by spring clamps 18' fixed to the web.

By this construction the plate 15 is held rigidly against all but an upward pull, but it is capable of removal by a sufficient pull upward.

Cemented or otherwise rigidly secured to the plate 15 is a comparatively thick circular sponge disk 16, which, by reason of the non-rotatable nature of the plate 15 to which the sponge is secured is also non-rotatable but is removable vertically with plate 15. The plate 15 and sponge disk have registering central holes through which the shaft 10 revolvably passes.

Mounted on the shaft 10 is a circular metal plate 17 of approximately the same diameter as plate 15, which is fixed to rotate with the shaft; here shown by the formation of screw threads on the shaft, on which is screwed a nut 18 upon which the plate 17 rests, and is locked in fixed relation to the shaft by a nut 19 which is screwed down tightly against the plate to clamp the plate 30 between the nuts.

Cemented or otherwise rigidly secured to the under side of the plate 17 is a sponge disk 20 similar in size and shape to the sponge disk 16.

The golf ball, 24, shown by dotted lines in Figs. 35 1 and 3, is placed between the two sponge disks 16 and 20 by lifting off the cover 6 and withdrawing therewith the shaft 10, plate 17 and sponge 20 and when the ball is positioned upon sponge disk 16 the members 6, 10, 17 and 20 are 40 replaced, as shown in Fig. 1. The sponges 16 and 20 are sufficiently soft and yielding that the weight of cover, shaft and plate 17, cause the golf ball to be pressed into both sponges as shown in Fig. 1.

Should the weight of the above parts prove insufficient additional weights shown by dotted lines 21 may be added to rest upon the plate 17.

In the operation, with the golf ball placed and parts of my device assembled as above described 50 and shown, and the container 5 supplied with soap suds over the plate 17, a rotation of the shaft 10 by the manual turning of crank 11 causes the golf ball to be rubbed by the sponge 20 and rolled around upon and rubbed by the sponge 16 to 55

quickly and thoroughly clean all parts of the surface of the ball.

When cleaned the ball is removed by a reverse operation to that of its introduction into the device.

5 The container 5 may be made out of metal, clay or other material but will preferably be of transparent glass in order that the ball may be observed through the walls of the container to dis- close when it is clean.

10 Preferably the top 6 will be upwardly tapering and the body elongated to simulate the shape of a soft drink or other bottle for advertising purposes of which the dome 8 is the mouth and seal.

While the above indicated structure will per- 15 form entirely satisfactory, it may be preferable to supplement the sponge 16, with a plurality of grooves 25, here shown as three in number and arranged to cross the normal circumferential path of the ball 24 as it may be carried around the pad 20 by the upper pad 20. By so placing the grooves 25, the ball will be given a rotation transversely of its circumferential path so that the outer area of the ball will be more quickly and completely brought into contact with the faces of the two 25 pads. In reference to the material of the pads 16 and 20, this material may comprise a number of substances such as vegetable sponges, sponge rubber, and any other resilient material allowing itself to be compressed to grip the ball as it travels 30 thereover.

Having thus fully described my invention what I claim is—

1. In a device for cleaning golf balls, the combination of a receptacle for containing a washing fluid, a cover for the receptacle, a web below the cover fixed within the receptacle, a plate above the web, spring clamps releasably securing the plate to the web, a sponge disk fixed to the plate, a crank shaft journaled in the cover and in the web, a plate fixed to the shaft within the receptacle, a sponge disk fixed to the last plate on the side next to the first sponge disk, said sponge disks receiving the golf ball between them.

2. In a device for cleaning golf balls, the combination of a receptacle for containing a washing fluid, a pair of horizontally disposed disks in said container, one disk being relatively fixed and the other disk shiftable vertically above the first disk, each of said disks having resilient opposing pads between which a golf ball may be gripped and carried circumferentially around between the pads by rotation of the shiftable pad, the wall of the container serving to maintain the ball between the pads, and at least one of said pads having grooves in its ball contacting face, the grooves being across the normal circumferential line of travel of the ball whereby rotation of the ball transversely of said line may be induced.

GEORGE A. BRILLHART. 30
